(57) **CLAIM**

The ornamental design for a keg grill and smoker as shown and described.

DESCRIPTION

FIG. 1 is an upper, front, left-side perspective view of a keg grill and smoker showing my new design.

FIG. 2 is an upper, rear, left-side perspective view thereof.

FIG. 3 is a top plan view thereof.

FIG. 4 is a bottom plan view thereof.

FIG. 5 is a front elevational view thereof.

FIG. 6 is a rear elevational view thereof; and,

FIG. 7 is a left-side elevational view thereof; of which the right-side elevational view is a mirror image.
